MOTION PICTURE EXHIBITOR CABINET

E. Burton Benjamin, Highland Park, Ill., assignor to
Urban Industries, Inc., Louisville, Ky., a corporation of
Kentucky

Filed Sept. 5, 1962, Ser. No. 71,568

Term of patent 3½ years

(Cl. D80—11)

FIGURE 1 is a front elevational view of a motion picture exhibitor cabinet showing my new design;

FIGURE 2 is an elevational view taken from one side thereof; the opposite side being a mirror image of the side shown;

FIGURE 3 is a reduced scale rear elevational view thereof;

FIGURE 4 is a top plan view thereof;

FIGURE 5 is an enlarged fragmentary perspective view of a portion of the front thereof; and

FIGURE 6 is a sectional view taken along line 6—6 portion of the front thereof.

I claim:

The ornamental design of a motion picture exhibitor cabinet, as shown and described.
